INVENTOR
Frank E. Boehncke
BY
P. Frank Sonnich
ATTORNEY

UNITED STATES PATENT OFFICE.

FRANK E. BOEHNCKE, OF WOODHAVEN, NEW YORK.

WINDOW SCREEN.

Application filed October 1, 1920. Serial No. 414,111.

To all whom it may concern:

Be it known that I, FRANK E. BOEHNCKE, a citizen of the United States, residing at 58 Vanderveer Avenue, Woodhaven, county of 5 Queens, and State of New York, have invented certain new and useful Improvements in Window Screens, of which the following is the specification.

This invention relates to window screens 10 and has for its object the provision of simple and serviceable means for screening an entire window opening and at the same time permitting easy manipulation for permitting access to be had to blinds, awnings, shutters, 15 clothes-lines or the like, associated with the window.

Another object is to provide a window screen for the above purpose adapted to be readily made and applied in position either 20 inside or outside of the window.

A further object is to provide a window screen adapted to be moved in respect to the window, without it being necessary to detach the screen from the window casing, so as to 25 uncover substantially the entire window for cleaning or repair, and to permit a portion of the screen to be moved relative to the entire screen portion to provide an opening through the screen and thereby offer ready 30 access to the window for opening and closing the same or to shutters, awnings and clothes-lines outside of the window for the manipulation thereof.

My invention further contemplates a window screen having the aforesaid characteristics and advantages which is so constructed that the components thereof may be readily cleaned so that the structure will meet the most rigid sanitary requirements.

My invention accordingly consists in the features of construction, combinations of elements and arrangement of parts which will be exemplified in the construction hereinafter set forth, and the scope of the invention of which will be indicated in the appended claim.

Similar reference characters refer to similar parts throughout the several views of the drawings, and in which is shown one of the 50 various possible embodiments of this invention.

Figure 1 is a plan view illustrating the screen mounted on a window casing inside of the window, the screen being in completely closed position.

Figure 2 is a fragmentary cross-sectional view on the line 2—2 of Fig. 1.

Figure 3 is a fragmentary detail in perspective of the two smaller swinging screen portions, and

Figure 4 shows in cross section the free edges of the smaller movable screen portions when in closed position.

Referring to the drawings, the window screen comprises a rigid rectangular frame 1 adapted to snugly fit the interior of a window casing 2 and to be hinged thereto at one side by means of hinges 3 whereby this frame may be swung away from the window. A latch 4 may be provided as at 5, whereby frame 1 may be locked in closed position. Frame 1 may be supplied with a suitable handle 6 or the like to aid a person in the opening and closing of the screen as a whole. Screen frame 1 carries a rigid transverse 75 frame member 7 so placed with respect to the top and bottom of the screen frame that when the screen is in closed position inside of a window, the window may be readily opened and closed from below this transverse member. The transverse member divides frame member 1 into two portions, the upper portion being permanently screened by any suitable foraminous screening material, such as mosquito netting or the like, 80 but the lower portion is provided with a pair of secondary screen frames 8 and 9, frame 8 being hinged to one vertical member of frame 1, as by hinges 10, and frame member 9 being hinged to the other vertical 85 member of frame 1, as by hinges 11. Frame members 8 and 9 are individual screens of any suitable material, and are adapted, when in closed position, to completely cover the lower portion of the main screen and that 90 portion below transverse member 7. Members 8 and 9 may be independently movable on frame member 1 and should preferably always be movable interiorly of the window with which they are associated so as to permit, when open or partially open, free and ready access to awnings, shutters, clothes-lines or the like. The lower edge of the transverse frame member 7 is preferably rabbetted to register with the complementary 100 upper edges of the frame members 8 and 9 as shown at 12. The abutting edges of said frame members 8 and 9 are likewise rabbeted so that when the said frame members are 105 in closed position a seam or joint is formed

110

between said frame members 8 and 9 and between said members and the transverse member 7 through which an insect may not enter, the frame members 8 and 9 being held in closed position by means of a latch 13 which may be positioned on the transverse member 7 as herein shown. The lower edges of the frame members 8 and 9 and the upper edge of the bottom frame member 7^b are preferably plain surfaces, in order to eliminate the possibility of the accumulation of dust and dirt which would find ready lodgment upon the upper edge of said frame member 7^b were it provided with a rabbeted or similar surface. Furthermore by providing the latter member with a plain surface it may be readily cleaned. Thus it will be seen that by this construction a structure is provided which will meet all sanitary requirements. To limit movement of the screen portions 8 and 9 relative to the main screen member 7^b and to maintain the said movable screen portions 8 and 9 in functioning position, I provide a stop 14 which is fixed to said member 7^b against which the frame member 8 abuts when the screen portions 8 and 9 are in closed position. Weather strips 15 may be applied to the window casing in the usual way to limit movement of main screen portion 1 inward of the casing and to prevent insects or the like from passing between screen frame 1 and the window casing.

In Fig. 2 are shown lower window sash 16 and upper window sash 17 in lowered position.

It is obvious that a screen constructed in the above manner and for the aforesaid purposes may be mounted either inside or outside of the window. When mounted on the inside of the window, transverse member 7 should be high enough in the frame to permit of the free and easy manipulation of the window from below that member when frame members 8 and 9 are open. When the screen is to be mounted on the outside of the window frame members 8 and 9 should be reduced vertically to permit of their being swung inwardly and below the window

sashes when both are in raised position and transverse member 7 should be positioned accordingly.

The pivoting of the main frame member 1 to the window casing permits the entire screen to be swung away from the window and thereby give unobstructed passage through the window, and when the frame is positioned inside of the window to permit free access to the window for washing or to the casing for the repair or adjustment of the window ropes, and movement of one or both of screen members 8 and 9 inwardly permits of ready access to shutters, awnings, clothes-lines and the like on the outside of the window for their manipulation.

Thus it is seen that an inexpensive, convenient and serviceable window screen has been provided and one which accomplishes the desired objects above mentioned.

Having thus fully described my invention what I claim as new and desire to secure by Letters Patent is:

The combination with a window frame of a screen comprising a main frame coextensive with the opening in the window frame and pivotally connected to said window frame, said main frame having side members and top and bottom members, a transverse member fastened to the side members intermediate the top and bottom members thereby providing two openings, screening permanently covering one of said openings, and a pair of secondary frames each having side members and top and bottom members, a side member of each of the secondary frames being hinged to a side member of the main frame, the secondary frames, when swung inwardly, closing the lower opening in the main frame, that portion of the transverse frame member which cooperates with the members of the secondary frames and the cooperating portions of the secondary frames being rabbeted, the portions of the bottom and side members of the main frame and of the secondary frames which cooperate being smooth.

FRANK E. BOEHNCKE.
